UNITED STATES PATENT OFFICE.

JOHN H. MASON, OF HEAVENER, OKLAHOMA.

FUEL-VAPORIZING DEVICE FOR INTERNAL-COMBUSTION ENGINES.

1,257,089.

Specification of Letters Patent. Patented Feb. 19, 1918.

Application filed June 30, 1917. Serial No. 178,020.

To all whom it may concern:

Be it known that I, JOHN H. MASON, a citizen of the United States, residing at Heavener, in the county of Le Flore and State of Oklahoma, have invented certain new and useful Improvements in Fuel-Vaporizing Devices for Internal-Combustion Engines, of which the following is a specification, reference being had to the accompanying drawings.

This invention relates to a device for vaporizing kerosene and other relatively heavy fuels for use in internal combustion engines, and has for its primary object to provide means whereby the engine may be started on highly volatile fuel such as gasoline, and then utilizing the heat of the exhaust gases for the vaporization of the kerosene or other relatively heavy fuel.

It is another and more particular object of the invention to provide a carbureter having separate gasoline and kerosene chambers, the exhaust manifold of the engine being provided with a heating chamber, a conduit connected to said heating chamber with the gasoline and kerosene chambers of the carbureter, and a manually operable valve whereby communication between either of the latter chambers and said conduit may be closed.

It is also another object of the invention to provide an apparatus for the above purpose, which is relatively simple in its construction, highly efficient and reliable in operation, and may be manufactured and applied to the ordinary motor vehicle at relatively small cost.

With the above and other objects in view, my invention consists in the novel features of construction, combination, and arrangement of parts to be hereinafter more fully described, claimed, and illustrated in the accompanying drawings, in which,

Figure 1 is a side elevation illustrating the preferred embodiment of my invention as applied to a motor vehicle engine;

Fig. 2 is an enlarged sectional view taken on the line 2—2 of Fig. 1;

Fig. 3 is an enlarged vertical section through the carbureter; and

Fig. 4 is a section taken on the line 4—4 of Fig. 3.

Referring in detail to the drawing, 5 designates the exhaust manifold of the engine which is provided with the usual connections shown at 6 to the exhaust ports of

the several engine cylinders. Below this manifold there is provided, preferably as an integral part of the manifold, a casing 7 which receives the fresh charge of gas, said casing being provided with the openings or ports 8 in one wall, through which the gas passes to the intake ports of the engine cylinders. Upon one side of the exhaust manifold 5, a longitudinally extending wall 9 is disposed in spaced relation to the manifold and preferably integrally formed or cast with the manifold wall. Thus, a heating chamber is formed, of which the manifold wall constitutes one of the side walls. The wall 9 may constitute a continuation of the wall of the casing 7, the heating chamber being separated from the gas intake chamber by a longitudinally extending web or partition indicated at 10.

The carbureter is provided with a gasoline receiving chamber 11 and a chamber 12 to receive kerosene or other relatively heavy hydrocarbon fuel. Supply pipes 13 and 14 respectively, extending from separate tanks or reservoirs, are connected to these chambers, and the supply of the fuels is controlled by the usual valves 15 operated by floats 16 disposed in the respective fuel chambers. The fuel is drawn by suction in the usual manner through the passages 17 and 18 respectively, into the nipple or extension 19 from the casing of the carbureter, said passages being separated by a central division wall 20. In the nipple 19, a valve plate 21 is slidably mounted in suitable grooves or channels, said plate being movable through an opening 22 in the division wall and operated by means of any suitable connections from the dash board of the vehicle body. 23 and 24 designate air inlet passages communicating with the respective gas passages 17 and 18, and valves 25 are arranged in these passages and operable by

any approved means to control the inlet of atmospheric air for mixture with the gas. The usual needle valves, indicated at 26, are also provided for controlling the passage of the fuel from the fuel chambers into the passages 17 and 18. A throttle valve, indicated at 27, is arranged in the nipple 19 beyond the division wall 20, so that the volume of the gaseous mixture entering the heating chamber 9 may be varied as desired.

A pipe or conduit 28 is suitably connected at one of its ends to the end of the nipple 19 and has its other end connected to a port

2
or opening 29 in one end of the wall of the heating chamber. A pipe 30 is similarly attached to an outlet opening at the other end of this chamber and is centrally connected to the wall 7 of the intake casing.

Having above described the several structural features of my invention, its operation will be understood as follows. When the engine is started, the sliding valve 21 is moved to close the passage 18 communicating with the kerosene chamber of the carbureter so that a mixture of gas and air will be drawn through the passage 17 and the conduit 28 into the heating chamber, from which it passes through pipe 30 to the several intake ports of the engine cylinders. After the wall of the exhaust manifold has become highly heated by the hot exhaust gases, the valve plate 21 is moved to the position shown in Fig. 3 to close communication between the pipe 28 and the gasoline chamber 11 so that a mixture of kerosene and air will now be drawn from the chamber 12 through this pipe into the heating chamber 9. In the passage of the mixture through this chamber, the same is highly heated and vaporized by contact with the wall of the exhaust manifold so that when it is finally delivered through the pipe 30 connected to the opposite end of the heating chamber, into the intake casing 7, the mixture is in a properly vaporized condition for ready combustion. Thus, when the kerosene vapor is compressed within the several cylinders it will, when exploded by the spark, exert the same driving force upon the engine pistons as in the use of gasoline vapor. It will thus be apparent that, by means of my invention, considerable economy may be effected by the use of low grade fuels in the operation of the engine. In the accompanying drawings, I have illustrated a construction and arrangement of the heating and intake chambers which is particularly adapted for use in connection with the Ford type of automobile, but it is to be understood that such arrangement is capable of some modification as may be required in order that the invention may be adapted to other constructions of motor vehicle engines. The several parts of the apparatus are, however, of simple form, efficient and reliable in their op-

eration, and can be manufactured at comparatively small cost. The construction of carbureter herein illustrated is not absolutely essential to the proper operation of the apparatus, but various other forms of the several valves and operating means therefor may be substituted. It is, therefore, to be understood that while I have herein shown and described one practical embodiment of the device, the same is nevertheless susceptible of considerable modification, and I, therefore, reserve the privilege of adopting all such legitimate changes as may be fairly embodied within the spirit and scope of the invention as claimed.

Having thus fully described my invention, what I desire to claim and secure by Letters Patent is:

1. The combination with an internal combustion engine having an exhaust manifold and a chamber extending longitudinally along one side of said manifold, of an intake manifold below the exhaust manifold, the wall of the exhaust manifold constituting the top wall of the intake manifold, a gas supply pipe connected to one end of the chamber on the exhaust manifold, and an outlet pipe connected to the other end of said chamber and to the intake manifold centrally thereof.

2. The combination with an internal combustion engine having an exhaust manifold, of a wall extending longitudinally along one side of said exhaust manifold and integrally connected therewith to form a heating chamber, an intake manifold disposed below the exhaust manifold, a carbureter having gasoline and kerosene chambers, a common pipe connection between said chambers and one end of the heating chamber, a manually shiftable valve to close communication between one of said chambers and said pipe and open communication with the other chamber and the pipe, and a pipe connection between the other end of the heating chamber and the intake manifold.

In testimony whereof I hereunto affix my signature in the presence of two witnesses. 100
JOHN H. MASON.
